(57) **CLAIM**

I claim the ornamental design for a light-magnetism harmonizer, as shown and described.

DESCRIPTION

FIG. 1 is a front, right, and top perspective view of a light-magnetism harmonizer showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a right, rear, and bottom perspective view thereof;

FIG. 9 is a cross-sectional view of the light-magnetism harmonizer, taken along line 9-9 in FIG. 2 thereof; and, FIG. 10 is a perspective view of the light-magnetism harmonizer in use.

The broken lines in the drawings illustrate portions of the light-magnetism harmonizer which form no part of the claimed design.
